Assistant Examiner—Melody Brown

Attorney, Agent, or Firm—S. Michael Bender

[57] **CLAIM**

The ornamental design for a magnetic tow hitch kit, as shown.

DESCRIPTION

FIG. 1 is a front elevational view of the magnetic tow hitch kit showing my new design;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof; and,
FIG. 7 is a perspective view thereof, it being understood that the broken lines are for illustrative purposes only and forms no part of the claimed design.
